UNITED STATES PATENT OFFICE.

FRANCIS CLINGMAN, OF ALBANY, OREGON.

APPLE PARING AND CORING MACHINE.

SPECIFICATION forming part of Letters Patent No. 329,363, dated October 27, 1885.

Application filed July 10, 1885. Serial No. 171,166. (No model.)

To all whom it may concern:

Be it known that I, FRANCIS CLINGMAN, of Albany, in the county of Linn and State of Oregon, have invented certain new and useful 5 Improvements in Apple Paring and Coring Machines; and I do hereby declare that the following is a full, clear, and exact description thereof, reference being had to the accompanying drawings, and to the letters of reference 10 marked thereon, which form part of this specification, in which—

Figure 1 is a top plan view. Fig. 2 is a vertical section of the same on line $x x$, Fig. 1. Fig. 3 is a bottom plan view. Fig. 4 is a vertical section on line $y y$, Fig. 1. Figs. 5, 6, 7, 15 8, and 9 are details of various parts. Figs. 10, 11, 12, and 13 represent detached views of the carriage and the paring, slicing, and coring devices.

20 This invention relates to improvements in machines for peeling, coring, and slicing such fruit as apples and pears; and it consists in the construction and novel arrangement of parts hereinafter described, and pointed out 25 in the appended claims.

Referring to the accompanying drawings by letter, A designates the main frame of the machine, of general rectangular shape, and provided with the bed-plate A', through the 30 opening $a a$ of which it may be attached by screws or pins to the edge of a table or other proper support.

B is a wheel, the shaft b of which is journaled in one of the side clips, a' , of the main frame, and has secured to its outer end a crank-handle, b' , by means of which it is rotated. The wheel B has upon the inner circumference of its rim the interior gear-teeth, b^2 , which mesh with the pinions C and D, the shafts C' 35 and D' of which are journaled transversely in the main frame, and are hereinafter described. The shaft C' is the main or driving shaft of the machine, and is journaled in the side clips, a' , of the main frame, and provided with the worm-thread c , as shown. The shaft D' is 40 journaled in an upright from the side clip, a' , of the main frame, and in a proper extension, a^2 , therefrom. The said shaft is arranged to carry the fruit to be pared and cored, and is 45 hereinafter more fully described.

E is a transverse bar, rectangular in cross-

section, fixed into and forming part of the main frame, and vertically above the main shaft C'.

F is a transverse bar vertically above the 55 bar E, and having its ends secured to uprights rising from the side clips, a' , of the main frame.

G is a carriage bearing the peeling device, and adapted to travel on the bar E by the following means: The carriage has a block-shaped 60 body, g , provided with an upward extension, g' , in which is formed a transverse opening, g^2 . The bar E passes through this opening, so that the carriage rides on the said bar.

g^3 is a standard rising from the extension 65 g' , and having a bar, F, passing through a proper opening in it, and g^4 is an arm rising vertically from the extension g' . The said arm serves a purpose hereinafter explained.

H is an arm pivoted to the side of the carriage-body, and carrying a rod, h , passing through a longitudinal opening in it, and rendered longitudinally adjustable by means of a nut, h' , on the threaded end of the arm H, which nut bears against the end of the rod h , 70 and makes it stand farther in or out, as desired. The point h^2 of the rod h engages with the worm-threads c of the driving-shaft C', so that the carriage G is made to travel on the bar E when the driving-shaft rotates. The 80 worm has its threads farther apart near its outer end, so that the paring and cutting knives will be more quickly moved up against the fruit, and when the corer and paring-knife are at work the end h^3 of rod h enters the 85 worm where its threads are closer together.

h^4 is a pin standing outward from the body of the carriage G, and engaging against the lower edge of the arm H, so as to prevent the latter from being forced downward out of engagement with the worm-thread. 90

h^4 is a coiled spring on the bar F, between the side clips, a' , adjacent to the wheel B and the standard g^3 of the body of the carriage.

h^5 is the beveled inner end of the worm- 95 thread c . When the wheel B is rotated by means of its crank-handle b' , the main shaft C' is rotated by means of its pinion C, and the interaction of the worm-thread c and point h^2 of the detent-bar h causes the carriage G to 100 travel inward on the bar E, which thereby compresses the coiled spring h^4 . When the

point h^2 reaches the beveled inner end, h^5 , of the worm, the thread runs off the point h^2 , the outer end of the arm H falls, and the action of the coiled spring h^4 drives the carriage outward to its former position.

h^6 is a leaf-spring secured to the main frame, which spring impinges on the outer arm, H , and forces the point h^2 to again engage the worm-thread.

10 h^7 h^8 are arms on the rod h , which arms strike against the arm H and prevent the rod from rotating entirely in its bearing, while having enough freedom of motion to accommodate itself to the worm.

15 I is the arm of the peeling or paring knife, which arm is pivoted at i on the body of the carriage G , between the same and the arm H . The arm I has an upward extension, I' , Fig. 7, at its inner end, by means of which it may be

20 turned on its pivot i , so as to disengage the knife from the apple. The outer part of the arm I also extends upward in a gentle curve, and bends over laterally toward the crank and coring mechanism at its end. The lower edge

25 of the bent portion is formed into a knife-edge, i' , as shown. It will thus be seen that the paring-knife i' will cut into the apple as it passes the said arm in all positions, the directing-block i^2 forming a guard to keep the knife, 95

30 i' from cutting too deep. The block i^2 is pivoted at its lower end to the downwardly-bent shorter arm of the paring-knife, its upper end and sides lying against the edge of said knife, and having but a limited degree of motion

35 outward therefrom.

i^3 , Fig. 8, is a coiled spring attached to the central part of the arm I , and at its upper end to the carriage, or to a part of the machine fixed to the carriage, and hereinafter described. The said spring draws the knife-edge up against the fruit. The directing-block i^2 is so balanced on its pivot as to drop back from the edge of the paring-knife and allow the pieces of paring and bruised apple to fall.

40 J is a collar provided with a circumferential groove, j , and arranged to move longitudinally upon while turning with the shaft D' . The said collar is located on the shaft at the outer side of the extension a^2 , and has standing inward from its inner face the parallel prongs j' , which pass through openings in a collar, j^2 , fixed on the shaft D' , and lying in a recess in the extension a^2 . The fruit is secured on the prongs j' , in the usual manner.

45 j^3 is a cylindrical block on the end of the shaft D' , provided with longitudinal grooves, in which the prongs j' lie, as shown.

K is a lever, pivoted at k upon the bed-plate A' , and having its inner arm bifurcated at its 60 end and embracing the shaft D' .

k' is a clutch-piece having a central opening, which moves freely on the shaft D' . The arms of the clutch-piece k' pass over the arms of the bifurcations of the lever K , and, bending inward, enter the groove j of the collar J . As the carriage G moves inward, the arm g^4 thereon strikes against the longer arm of the

lever K , over which the clutch-piece k' passes, and moves the said lever on its pivot. The lever then, by means of the clutch-piece k' , 7c pulls outward the collar J and attached prongs j' , so that the block j^3 passes beyond the ends of the prongs and forces off the core of the fruit fixed upon the prongs, the core having been already cut loose by a device hereinafter described. When the carriage springs away to its normal position, as described, the lever K is released, and the action of the coiled spring k^2 forces the lever inward again, the said spring being secured to the lever and to the base of a hook, k^3 , pivoted on the main frame, and adapted to catch against a pin, k^4 , on the lever K , and prevent the latter from going too far inward. The spring k^2 pulls the hook k^3 and pin k^4 into engagement when 85 they are in proper relative positions.

L is a lever-arm pivoted at its outer end on the base-plate A' , and having its inner end provided with the downwardly-extending arms l , l , Fig. 6, which lie on either side of 90 the prongs j' , as shown.

l' is a link, pivoted at its ends on the levers K and L in such manner that the motion of the former in one direction makes the latter move in the opposite direction and push the fruit, when peeled, cored, and sliced, off the prongs j' . 95

M is a bar, preferably rectangular in cross-section, and having its inner end made square, and bolted or otherwise properly secured to 100 the upward extension g' of the carriage G , so that the said bar travels with the carriage. The outer end of the bar M is formed into a head, m , for a purpose hereinafter explained.

N is a hollow semi-cylindrical receiver having a block, n , secured to its inner edge, which block is bored longitudinally and fitted upon the bar M so as to travel thereon. 105

n' is a coiled spring on the bar M , bearing against the head m of the latter, and against 110 the adjacent side of the block n . The inner end of the bar M , which is bolted to the carriage G , has secured to it and standing out from its lower side the L-shaped stem o of the slicing device O . The said stem, after running out horizontally to a proper distance, 115

bends vertically upward, and has its inner edge, o' , properly beveled to form a slicing-knife, as shown. The upper end of the vertical portion of the stem o is formed into a 120 short tube, o^2 , which stands concentric with the prongs j' , and has sufficient diameter to pass over the said prongs when moved inward. The inner edge of the tube o^2 is beveled to a cutting-edge and given a proper 125 shear, forming the coring-knife.

P is an arm standing horizontally outward from the block n , and provided at its end with a tubular portion, p , which travels with the receiver N , moving concentrically with the 130 corer-tube o^2 .

p' is a stop or presser-block secured in the inner end of the tubular portion p , and having its face convexed or rounded, as shown.

The inner and longer arm *l* of the lever *L* is so situated as to strike against the lug *p*², standing from the block *r*, when the said lever moves outward, to drive the receiver *N* outward against the spring *n'*.

Q is a bar standing inward from the bed-plate *A'*, and so situated that the upward extension *I'* of the peeling-knife may press against it as the carriage *G* moves inward, thus moving the peeling-knife outward as the diameter of the fruit passing under it increases. The apple being fixed on the prongs rotates therewith on the shaft *D*, the carriage *G*, bearing the paring or peeling knife, advances, and while it is paring the apple the coring-tube *o'*, which stands immediately behind it, separates the core, and the slicing-edge *o'* is cutting that part of the apple up that has been pared. As the carriage *G* advances, the receiver *N* also advances, and the presser-block *p* in the tube *p* is pressed against the apple, holding it on the prongs. When the receiver is thrown out again with the carriage, it carries with it the slices of apple that have fallen from the slicing-knife.

R is a cutting-edge made on the arm *P* of the tube *p*. The said edge cuts apart the spirals which have been cut by the paring-knife. The coiled spring *n'* on the bar *M* is to push the tube *p* and presser-block *p'* against the core of the apple being operated upon, so that whether the apple be large or small its parts cannot, even when cored and sliced, fall between the carriage or prongs *j'* and the receiver. The receiver *N* is hollow and semi-cylindrical, having attached to its outer and upper corners a curved band extending out from it, the use of said band being to stop the momentum of the cut apple and to cause it to drop into the receiver, instead of going over it. The cut apple then drops from the outer edge of the receiver into any suitable receptacle placed for it. The apple rotates with the prongs *j'* and the carriage advances, the knife *i'* paring the apple, the tube *o'* coring the apple, and the knife *o'* slicing the apple spirally, all the while the presser-block *p'* pressing against the end of the apple opposite the stem. As the receiver passes under the apple the knife *R* cuts apart the spirals into slices proper, which fall into the receiver and pass over its outer edge into any receptacle. The carriage and receiver now

spring back, actuated by the described mechanism, and the prongs *j'* are drawn outward over the block *j*³, which drives the core from 55 between the prongs and leaves them ready to receive another apple.

Having described my invention, I claim—

1. In an apple-parer, the combination of the main frame *A*, provided with the bed-plate *A'* 60 and having attached the spring *h*⁶, and the main shaft *C'*, provided with the worm *c*, with the carriage *G*, arranged to travel on the transverse bars forming part of the main frame, and having attached the pivoted arm *H*, provided 65 with the rod *h*, actuated by the worm *c*, and paring, coring, and slicing devices, substantially as described.

2. The combination, with the rotating shaft *D'*, provided with the collar *j*², and having the 70 cylindrical block *j*³ on its inner end, and the loose collar *J*, provided with the flanges *j*, of the lever *K*, pivoted on the bed-plate *A'*, the clutch-piece *k'*, and the carriage *G*, moving laterally on the main frame and provided with a 75 lug, *g'*, arranged to strike against the lever and move it outward, substantially as specified.

3. The combination, with the rotating shaft *D'*, arranged to hold the fruit, the laterally-moving carriage *G*, and the lever *K*, moved 80 laterally by the carriage, of the link-bar *l*' and the lever *L*, having the downwardly-extending arms *l l*, adapted to press the pared and sliced fruit off the shaft *D* when actuated by the movement of the lever *K*, all substantially as specified. 85

4. The combination of the rotating shaft *D'*, the carriage *G*, carrying the paring devices and moving laterally on the main frame, the levers *K* and *L*, and link-bar *l*', with the bar *M*, secured to the carriage and carrying the coring and slicing devices, the fruit-receiver *N*, arranged to slide on the bar *M*, and the coiled spring *n'*, adapted to move the receiver *N* in the opposite direction to that in which it is 95 moved by the lever *L*, all substantially as specified.

In testimony that I claim the foregoing as my own I affix my signature in presence of two witnesses.

FRANCIS CLINGMAN.
